UNITED STATES PATENT OFFICE.

WILLIAM L. GUMPRECHT, OF HARTFORD, CONNECTICUT, ASSIGNOR TO UNDERWOOD COMPUTING MACHINE COMPANY, OF NEW YORK, N. Y., A CORPORATION OF NEW YORK.

TYPEWRITING-MACHINE.

1,388,253.

Specification of Letters Patent. Patented Aug. 23, 1921.

Application filed March 22, 1917. Serial No. 156,595.

To all whom it may concern:

Be it known that I, WILLIAM L. GUMPRECHT, a subject of the King of Great Britain, residing at Hartford, in the county of 5 Hartford and State of Connecticut, have invented certain new and useful Improvements in Typewriting-Machines, of which the following is a specification.

- This invention relates to an improvement 10 in typewriting machines, and is herein illustrated as applied to a combined typewriting and computing machine, and more especially to means for preventing a premature tabulating movement from one zone to another 15 zone, that is, to prevent such movement until a letter-space or digit-space movement of the carriage, incident to the previous striking of an alphabet key or numeral key, has been completed.
- 20 It may happen that where the operative strikes a tabulating key too soon after striking the last character key in a column or zone just written, the carriage feeds an extra or spurious letter-space movement when it 25 arrives at the new zone or major column. This extra feeding arises, in the Underwood typewriting machine structure, from the fact that the solid dog of the typewriter holds the typewriter carriage during part of the depression and early return stroke of a key, 30 with the result that the depression of a tabulating key at this time may catch the loose dog behind the escapement wheel, thereby letting the carriage feed a letter-space before 35 the loose dog catches the wheel, this being in addition to the usual letter-space after the loose dog catches. In other words, the overlapping of the action of a character key into the period of action of the tabulating key 40 might bring about an incorrect selection of the desired computing decimal column at the beginning of the new zone. Such an incorrect decimal column selection of the mechanism might cause both erroneous typewriting 45 and the running up of the digit into the wrong computing wheel, because the typist often writes the next character before looking at the position of the carriage.
- In order to avoid such mistakes, a lock is 50 provided for preventing the actuation of any tabulating key until the usual carriage-escapement mechanism has returned to its normal position, which will be at a time when the carriage has completed a letter-space 55 movement. To do this as herein illustrated,

a part of the mechanism in the application of Henry L. Pitman, No. 81,574, filed March 2, 1916 (now Patent No. 1,345,102, dated June 29, 1920), on which this case is shown as an improvement, is employed. In that 60 case the escapement mechanism for the carriage, or, stated more exactly, the loose dog, controlled the full-stroke mechanism for the numeral keys. This mechanism insured the complete depression and return of an actuated numeral key from the rocker carrying the fast and loose dogs of the escapement mechanism, and also effected locking of the numeral keys upon release of the loose dog from the tension exerted thereon by the carriage, when such release was produced by a return movement of the carriage due, for example, to the action of the back-spacing mechanism.

In the present disclosure, a blocking projection or obstruction is provided on the connection from the loose dog of the escapement mechanism to the full-stroke mechanism, which, when the escapement mechanism is but partially actuated, as when a numeral key 75 or other character key is still in play, lies in the path of a swinging arm connected to the tabulating-plunger release. This release is universal to all the tabulating plungers, and is operated in the usual way when any one of 80 the decimal-tabulating keys is operated to disconnect the carriage from the escapement mechanism.

Other features and advantages will hereinafter appear.

In the accompanying drawings, 90 Figure 1 is a vertical section from front to rear, with parts omitted to simplify the showing.

Fig. 2 is a skeleton perspective view, showing the escapement mechanism in a position in which it would be before a type-bar, such as a numeral type-bar, is raised to strike the platen with the loose dog in engagement with the escapement wheel. In this position, the locking projection is idle and does not prevent the actuation of the tabulating keys.

Alphabet keys 1 and numeral keys 2 depress key-levers 3 and rock bell-crank 4, so 105 as to swing type-bars 5 up rearwardly against the front side of a platen 6 mounted to rotate on a carriage 7. The carriage 7 is given a step-by-step letter-space movement due to the pull of a spring-barrel 8 con- 110

trolled by an escapement mechanism, indicated in general at 9. The escapement mechanism includes a rack bar 10 pivotally connected to the carriage 7 by means of arms 11, so as to swing into and out of engagement with a pinion 12. The rack bar 10 is normally in engagement with the pinion 12, but is capable of being disengaged therefrom when moving the carriage by hand a number 10 of letter-spaces in a letter-feeding direction, or when jumping the carriage a number of letter-spaces from zone to zone by tabulating mechanism.

The pinion 12 is controlled in its movement by an escapement wheel 13, to which it is connected by a one-way pawl-and-ratchet mechanism 14, Fig. 2. The escapement wheel 13 is controlled in its intermittent movement by a pair of dogs 15 and 16 carried by a rocker 17. The rocker 17 is moved rearwardly at each stroke of a character key by means of a universal frame 18 engaged by a heel 19 provided on each of the type-bars 5. The universal frame 18 is returned 25 by a spring 20 with the return of the character key actuated. This is the usual action of the Underwood typewriting escapement, but as its mechanism co-operates with the present invention, the action will be described a little more in detail.

The dog 15 is a fixed dog, while the dog 16 is a loose dog. That is to say, the dog 15 is rigid with the rocker 17, so as to positively intercept the escapement wheel 13 when brought in engagement therewith by a backward motion of the rocker 17 and the universal frame 18. Normally the dog 15 occupies the position shown in Fig. 1, with the loose dog 16, which is pivoted to the 40 rocker, as indicated in Fig. 2, in engagement with the escapement wheel. The loose dog, in this position, is limited by a stop 21 rigid with the rocker 17.

When the universal frame 18 is moved 45 rearwardly at the down-stroke of a character key, the fixed dog 15 is moved from its Fig. 1 position to its rearmost position in obstructing engagement with the escapement wheel 13. The loose dog 16 escapes the tooth 50 of the escapement wheel 13, with which it was in engagement, and is drawn by a spring 22 a distance sufficient to catch the next tooth on the escapement wheel.

Then, when the rocker 17 returns, the loose 55 dog 16 controls the escapement wheel by obstructing the movement thereof, but inasmuch as it has moved into engagement with the tooth in advance of the tooth with which it was previously in engagement, it 60 will be swung against the tension of its spring 22 until its further movement is prevented by the stop 21, thus permitting a step movement of the escapement wheel 13 and a letter-space movement of the carriage.

65 In addition to letter-space movements, the

carriage may also have jump or tabulating movements to skip over intervening letter-spaces from zone to zone, or from major column to major column. For this purpose, there are provided a series of decimal tabulating keys 23, which, when depressed, rock key levers 24 to thrust up plungers 25. Thus, when any one of the tabulating keys is depressed, it brings its plunger 25 to a projecting position where it will lie in the path of the next one of a series of carriage stops 26, adjustably mounted at letter-space intervals on a rack 27 carried by the carriage 7. In this way, the jumping of the carriage, from zone to zone, and to a particular decimal column or letter-space in a zone, is determined according to the particular decimal tabulating key 23 actuated.

In addition to writing digits, the numeral keys 2 control the computing operation in a manner more particularly described in application No. 81,574, above-mentioned. Considering this computing mechanism briefly, each numeral key 2 has on its lever 3 a cam plate 28, which swings a frame 29 an amount corresponding to the particular numeral key actuated. That is to say, the cam slots 30 of the plates 28 are graded in their form, so as to swing the frame 29, gradually increasing the amounts from a minimum for the "1" numeral key to a maximum for the "9" numeral key, forming an indexing or valuating mechanism.

The frame 29 has a pin 31 which normally engages in a socket 32 provided in an actuator 33. The actuator 33 comprises an interponent 34 loosely pivoted on a rock lever 35, and yieldingly held with its socket 32 in engagement with the pin 31 by means of a spring 36. This mechanism is such that the computing mechanism can be disconnected from the numeral keys, as when it is not desired to compute, and also when writing upper-case characters by the numeral keys. This silencing mechanism is not directly connected to the present invention, and so will not be described.

The actuator 33, when rocked an amount corresponding to the numeral key actuated, draws down on a link 36^a, so as to rock a bell-crank 37. This bell-crank advances a driving rack-bar 38 an amount corresponding to the numeral key actuated. The driving rack-bar rotates a gear 39 which is connected through a train of gearing 40 to drive a master wheel 41. Normally the rack-bar 38 is in engagement with the gear 39, and is carried forward while still in engagement therewith at the striking of the numeral key, but at the end of the key-stroke is carried out of engagement by means of a linkage 42 operated from the escapement rocker 17, which has a forked arm 43 engaging the linkage 42 for this purpose. This mechanism is more particularly described in the

application above-mentioned, and merely explained in general here, so as to connect the present invention with the previous improvements.

- 5 The master wheel 41 is stationary, but is arranged to drive successively a series of computing wheels 44, which drive dial wheels 45, so as to exhibit the numbers computed through a sight-opening in the casing 10 of a totalizer 46. The totalizer 46 is connected to the carriage 7, so as to have a step-by-step movement therewith, and thus bring the successive computing and dial wheels into register individually with the 15 master wheel 41. This connection includes a spring-pressed latch 47 which may be adjustably engaged between any two of a series of teeth at letter-space intervals on a rack 48 secured to the carriage 7.
- 20 In computing a plurality of columns or zones, a number of totalizers 46, corresponding to the zones computed in, may be used, or a plurality of master wheels 41, and the same totalizer brought into successive engagement with the several master wheels corresponding to the particular type of work being done. At any rate, a relative zonal movement between the totalizers and the master wheel or master wheels is obtained concomitantly with the zonal movement of the carriage, so that a series of horizontal or vertical columns can be computed at the same time that they are typewritten. Inasmuch as the decimal column and designation of the typewriting and computing mechanism is determined by the tabulating mechanism, if through a too rapid operation thereof, the action of the tabulating mechanism should overlap the action of 35 the escapement mechanism, then an incorrect position of the carriage and the traveling parts of the computing mechanism might occur, which, if unobserved, would cause an incorrect typewriting of the digits 40 and a running-up of the digits into the wrong computing wheels. In order to avoid such possibility, the tabulating mechanism is locked against operation whenever the escapement mechanism has been but partially 45 actuated, corresponding to an incomplete escapement movement of the carriage.
- 50 For this purpose, use is made of the release which disconnects the carriage 7 from the escapement when tabulating. That is to say, each of the tabulating plungers 25 is provided with a shelf 49 formed by notches in the plungers 25 to engage and operate an arm 50 universal to all of these shelves. This universal arm is secured to a shaft 51 55 to rock the same whenever any one of the tabulating keys, and thus, whenever any one of the plungers 25, is actuated. The shaft 51 has secured thereto an arm 52 which is connected to rock downwardly, so as to draw 60 down on a link 53 and thus rock a lever 54. The lever 54 has a roller 55 at its front end engaging under the rack 10 so as to raise the same out of mesh with the pinion 12. Thus the carriage can be drawn by its spring-barrel 8 a major amount until the next succeeding stop 26 comes into engagement with the projected plunger 25.
- 65 The shaft 51, which is rocked at this time, is also provided with a locking arm 56, which, if the escapement mechanism is still 70 in action, will prevent the rocking of the shaft 51 and thus prevent the action of the plungers 25 and the tabulating keys 23. This is done by a projection 57 underlying an extension 58 on the locking arm 56. The 75 projection 57 is formed on a bell-crank 58^a, which is normally held, when the carriage is at rest and no character key actuated, with the projection 57 out of reach of the extension 58 of the locking arm 56.
- 80 Indirectly the carriage spring holds the projection 57 in its non-locking position. That is to say, the bell-crank 58^a is connected by a link 59 to a follower 60 in the form of a bell-crank, having one arm connected 85 to the link 59 and the other arm engaging the back of the loose dog 16. The follower 60 is pivoted to the rocker 17, and swings back and forth with the loose dog 16 during an escapement movement of the rocker. 90
- 95 Normally the parts are in the position seen in Fig. 1, with the escapement wheel 13 engaging the loose dog and holding both the loose dog and the follower 60 against the stop 21, which corresponds to the normal position of the escapement mechanism, a stationary condition of the carriage so far as the escapement is concerned, and a non-locking position of the projection 57.
- 100 When the rocker 17 moves to bring the fixed dog 15 into engagement with the escapement wheel, the loose dog 16 is released and advances under the pull of its spring 22 to a position to engage the next escapement tooth. At this time, the follower 60 moves 105 up with the loose dog 16 due to the action of a spring 61 connected to the bell-crank 58^a. When moved in this way, the projection or obstruction 57 is brought to an interfering position underlying the extension 110 58 on the locking arm 56, thus preventing any possible action of the tabulating mechanism at this time when an incomplete action of the escapement mechanism has taken place.
- 115 120 When the escapement mechanism returns to its normal position, bringing the loose dog into engagement with the escapement wheel, the carriage spring which is the stronger, will operate, advancing the carriage a letter-space, rocking the loose dog 16 backward, carrying with it the follower 60, and thus withdrawing the obstruction 57 from beneath the extension 58 on the locking arm 56. Under these circumstances, 130

any one of the tabulating keys can be operated as desired, giving a zonal movement to the carriage and to the totalizers, which will be a correct one inasmuch as there is no 5 overlapping of the escapement and tabulating actions.

Incidentally, the same bell-crank 58^a, which carries the projecting obstruction 57, operates through a linkage 62 a full-stroke 10 double-acting pawl mechanism 63 which engages alternately on the down and up-strokes with oppositely-facing racks 64 and 65 provided on a hanger 66 on each of the 15 numeral keys 2. This mechanism is more particularly described in the application above-mentioned, and insures that the numeral keys be completely operated, so that there will be no error in the typewriting and computing. This operation is thus also controlled from the rocking frame of the 20 escapement mechanism.

It will thus be seen that the tabulating mechanism cannot be operated when the escapement mechanism has made but a part 25 of its action in spacing after writing the last digit in the zone, and further that the tabulating mechanism will not overlap the letter-space movement of the carriage, so that in jumping from zone to zone, both the carriage and the totalizers will be properly positioned, as selected by the tabulating keys, 30 to write in the correct digit column at the beginning of the new zone.

Also, as brought out in said application of 35 Pitman, movement of the loose dog 16 by its spring 22 and consequent shifting of follower 60 may be obtained when the escapement wheel 13 is relieved from the tension of the spring-barrel 8 by movement of the carriage in the return direction. Under such 40 conditions, locking of both the numeral keys and the tabulating keys would be effected.

Variations may be resorted to within the scope of the invention, and portions of the 45 improvements may be used without others.

Having thus described my invention, I claim:

1. In a machine of the character described a key controlled step-by-step escapement 50 mechanism, tabulating mechanism and an interlocking element for preventing the operation of the tabulating mechanism after a key has released the escapement and until said key has practically finished its return 55 movement, said interlocking element being so connected to the key as to remain stationary during part of the return movement of the key.

2. The combination with a traveling typewriter carriage, of escapement mechanism controlling step-by-step movements of said typewriter carriage, character keys controlling said escapement mechanism, a full-stroke mechanism for said keys to prevent 65 incomplete and overlapping action of said

keys, tabulating mechanism for controlling jump movements of said carriage for zonal selections, and a connection governed by said escapement mechanism, operating said full-stroke mechanism and locking said 70 tabulating mechanism when said escapement mechanism is in action.

3. The combination with a traveling carriage, of an escapement mechanism controlling step-by-step movements of said carriage, including a loose dog having reciprocating movements during an escapement action of said escapement mechanism, tabulating mechanism for controlling jump movements of said carriage, a locking arm 80 operated when said tabulating mechanism is operated, a follower moving back and forth with said loose dog, a link operated by said follower, a bell-crank operated by said link, and an obstruction on said bell-crank 85 moved, when said loose dog is released, to an interfering position with respect to said locking arm, so as to prevent an operation of said tabulating mechanism.

4. In a typewriting machine, the combination with a traveling carriage, of an escapement mechanism for controlling step-by-step movements of said carriage, keys controlling said escapement mechanism, tabulating mechanism for controlling jump movements of said carriage, an arm operated when said tabulating mechanism is operated, an obstruction for said arm, and means normally tending to move said obstruction into the path of said arm, to prevent its movement, said obstruction-moving means being under the control of said escapement mechanism whereby, after actuation of a key, no action of said tabulating mechanism can occur until the escapement mechanism has completed its movement.

5. In a typewriting machine, the combination with a traveling carriage, of an escapement mechanism for controlling step-by-step movements of said carriage, numeral keys controlling said escapement mechanism, said escapement mechanism including a loose dog, a follower connected to move with said loose dog, tabulating mechanism for controlling jump movements of said carriage, a locking arm connected to move with said tabulating mechanism, and an obstruction controlled in its movement by said loose dog through the intermediary of said follower acting to come in the way of said locking arm when said escapement mechanism is in action.

6. In a typewriting machine, the combination with a traveling carriage, of an escapement mechanism for controlling step-by-step movements of said carriage, numeral keys for controlling said escapement mechanism, a tabulating mechanism for controlling jump movements of said carriage including a release arranged to disconnect said 130

carriage from said escapement mechanism, and locking means for preventing the release of said carriage from said escapement mechanism while said escapement mechanism is in action under the control of a key, the locking element of said locking means remaining stationary during the return movement of the key.

7. In a typewriting machine, the combination with a traveling carriage, of an escapement mechanism for controlling step-by-step movements of said carriage, keys controlling said escapement mechanism, decimal-tabulating mechanism controlling zonal and 15 digit column selections or major movements of said carriage, said decimal-tabulating mechanism including a series of plungers, a locking member universal to all of said plungers operated when any one of them is actuated, obstructing means to coöperate with said locking member, and a spring tending to move said obstructing means to position to coöperate with said locking member, said escapement mechanism, when actuated by a 20 key, permitting said spring to act, said escapement mechanism also moving said obstructing means to normal position against the tension of said spring as said escapement mechanism completes its movement.

8. In a typewriting machine, the combination with a traveling carriage, of an escapement mechanism for controlling step-by-step movements of said carriage, keys controlling said escapement mechanism, tabulating mechanism for controlling jump movements of said carriage, including a series of plungers, an arm universal to all of said plungers operated when any one of said plungers is operated, a locking arm connected to be rocked by said universal arm and having an extension thereon, and a bell-crank having a projection thereon and con-

nected to be operated when said escapement mechanism is operated, to bring said projection into the path of said extension so as 45 to prevent the actuation of any of said plungers, and thus of said tabulating mechanism during the movement of said escapement mechanism under the control of a key.

9. In a typewriting machine, the combination with a traveling carriage, of an escapement mechanism for said carriage including an escapement wheel and a loose dog, said dog normally holding said wheel from movement, tabulating mechanism including keys 55 for controlling jump movements of said carriage, and means controlled from the loose dog of said escapement mechanism for preventing movement of a tabulator key until the loose dog returns to normal position. 60

10. The combination with a traveling carriage, of means urging said carriage in letter-feed direction, a carriage-escapement mechanism including a loose dog and a spring urging said loose dog in opposition to said 65 urging means, by which it is normally overcome, tabulating means, and means controlled by said loose dog to prevent actuation of said tabulating means.

11. The combination with a traveling carriage, of means urging the same in letter-feed direction, a carriage-escapement mechanism including a loose dog normally effective to hold said carriage against the action of said urging means, keys for actuating 70 said escapement mechanism, tabulating means, and means whereby actuation of said tabulating means may be prevented when said loose dog is relieved from the tension exerted by said urging means.
